IRONING BOARD HAVING FASTENING
MEANS

Alpha Perry Lantz, Washington, D. C.

Application February 6, 1947, Serial No. 726,888

7 Claims. (Cl. 38—103)

1

This invention relates to an improved hinged sectional ironing board of the type adapted to be folded into compact form rendering the same easily portable as in a suitcase or conveniently carried package.

The invention is designed to supply a common need of people traveling from place-to-place and stopping at hotels or apartments where ironing boards are not usually at hand, in meeting emergent or desired uses, it is simply necessary for one to unfold his own board, accompanying his package, and attach it to a convenient means, as the usual dresser drawer, in a position for ironing.

In an ironing board of the character referred to the sections of the board are rendered self-supporting, so to speak, that is, capable of performing their functions when extended and temporarily mounted at the inner end of the inner section of the board upon an opened drawer or the like, rendering it unnecessary to provide props or legs for the outer or free end section of the board, and leaving the board entirely unobstructed throughout for the slipping of garments thereover and therearound in the manipulation of the latter when ironing the same.

Two primary objects underlie the preferred embodiment of the invention, one being the special and novel formation of the hinging means connection the foldable sections of the board, enabling one section to be folded flat upon the other while affording no projecting elements above the plane of the top of the board when open to ironing position so that a continuous smooth top surface of the board may be mounted; and the other being the special and novel attaching means for connection with a dresser drawer and the like to support the drawer when in unfolded or ironing position, in a substantially level position, the latter means comprising hooks and shanks of minimum thickness, but sufficient strength, and means associated therewith for adjusting the hooks and shanks to accord with conditions found in the dresser or the like the adjusting means being located substantially within the area of the bottom of the inner section of the board to offer no substantial obstructions or projections below the plane of the bottom of the board that might interfere with the arrangement of the board when rested upon the top of the front of the dresser when the board is hooked into the dresser or the like, as by engagement behind the bridge piece, always present in a dresser or the like, and spanning the drawer opening.

In the said preferred embodiment of the in-

2

vention will be found important and advantageous details of construction and arrangement, all of which will be readily understood from the specific description hereinafter contained when read in connection with the accompanying drawings forming part hereof and wherein said preferred embodiment, and others, are illustrated.

In the drawings:

Figure 1 is a top view of the complete ironing board in unfolded or ironing condition.

Figure 2 is a bottom view of the same, detail parts being shown diagrammatically but completely illustrated in other figures.

Figure 3 is an enlarged bottom view of a portion 15 of the inner section of the board illustrating one of the attaching hooks and adjusting means therefor, it being understood that the hooks and adjusting means are identical wherever employed, a pair being sufficient in the present case.

Figure 4 is a sectional view through a central 20 longitudinal line of Figure 3.

Figure 5 is a transverse section on the line 5—5 of Figure 4.

Figure 6 is a transverse section on the line 6—6 25 of Figure 3 looking to the right or in the direction of the arrows.

Figure 7 is a similar view on the line 7—7 of Figure 3 looking in the opposite direction.

Figure 8 is a bottom section and elevation approximately on the line 8—8 of Figure 4.

Figure 9 is an end view of Figure 4.

Figure 10 is a fragmentary view of the abutting ends of the hinged sections of Figure 1, enlarged, to illustrate one of the hinge members, it 35 being understood that the hinge members are alike.

Figure 11 is an end view of the same.

Figure 12 is a vertical longitudinal sectional view on the line 12—12 of Figure 10.

Figure 13 is an end view of one of the abutting ends of Figure 10, parts of the hinged member being shown in section.

Figure 14 is an edge view of Figure 13, parts being broken away to show the inner construction of the abutting ends of the board.

Figure 15 is a vertical sectional view through abutting end portions of the board, the one section of the board being folded onto the other.

Figure 16 is a bottom view of Figure 10.

Figures 17 and 18 are respectively a cross section and a detached view illustrating a modified formation of hinge member.

Figure 19 is a detached elevation illustrating a modified form of the latching device of Figure 3.

Figure 20 is a bottom view of one of the hooks showing a slightly modified form of the shank thereof.

Referring more specifically to the drawings 29 indicates the outer section and 21 the inner section of the hinged sectional board, of a shape so that when the sections are unfolded, as in Figure 1, the same will be contoured in resemblance to a conventional ironing board. These sections are composed of suitable material, light in weight and strong and rigid in character, preferably wood, but in instances metal such as aluminum, or plastics may be utilized.

In fulfilling the purposes or objects of the present invention, it is desirable that the outer section 20 may be folded over and upon the top of the inner section 21 and to better enable this to be done it will be observed that the thickness of these sections be of substantial depth for three purposes (see Figure 12). First of all it is highly important that the outer section 20 be self-sustaining, that is, devoid of any such additional elements as legs or props to which end the abutting edges 22 extend well below the upper hinged edges 23 thereof to assist in relieving the strain on the hinges incident to downward pressure, in ironing, on the outer section 20; that the hinges be so arranged that the folding of the outer section 20 may be downwardly onto the inner section 21 without any interference in the movement of portions thereof to the complete folding of the sections; and also that the hinging be of a form to occupy a position completely below the plane of the upper surfaces of the board, when the sections thereof are extended for ironing, so that the combined ironing surfaces of the board will be in the same plane throughout and smooth, to avoid projecting parts above the upper surface of the board that would obstruct or interrupt the movement of an ironing implement over the ironing face of the board. Therefore, the upper adjacent corners of the meeting edges of the board are formed with recesses 24 of substantial length (Figure 10) at each side of the board in which metal hinge links 25 are located, the parallel arms 26 of the links passing through tubular keepers 27 formed by folding flat sheet metal upon itself (Figure 12) and securing the overlying flanges 28 and 29 thereof in complementary relatively shallow recess portions 30, in the upper faces of the board sections, so as to be flush and continuous with the ironing faces 31 of said sections. The flanges 28 and 29 being conveniently fastened through the body of the sections and through a reinforcing plate 32, similarly embedded in the bottom surfaces of the sections, by rivets 33. This arrangement and formation of hinging will permit the board sections, when extended, to be perfectly flat throughout their ironing face, will strongly support the outer section through the immediate hinge construction braced for considerable depth below the hinge by the contacting portions of the meeting faces of the sections below the hinge (Figure 12), and will permit the outer section to be folded flat onto the surface of the inner section without interference or obstruction (Figure 15).

To further strengthen the meeting ends of the sections 20 and 21, the lower plates 32 each carry lugs 34, adapted to underlie the opposite plate when the sections are opened to ironing position (Figures 2, 12 and 16), and preferably the metal of the plates 32 is carried upwardly and around the side edges of the sections 20 and

21 as shown at 35 to the top plates 29, and inwardly as at 36 to overlie or embed in the meeting ends of the sections 20 and 21. The wooden, or other portions of the material of the sections 5 is thus preserved against breaking, chipping or cracking under the changes or weight of throwing the outer section 20 to open position which may at times occur in careless or indifferent setting up and use of the board.

10 In folding the outer section 20 of the board over onto the section 21 thereof, it will be seen that as the section 20 is swung upwardly it will be at the same time raised with reference to the section 21 through the medium of the hinge links 15 25 and the upper adjacent corners of the board sections cannot interfere with each other during the folding movement of the board. Instead of having the hinge member 25 in the form of a 20 complete loop, as illustrated in Figure 10, the same may be of the formation illustrated in Figures 17 and 18 wherein it will be seen that the substitute for the link is formed of a U-shaped member 37 adapted to have its arms 28 each received into the bearing portion of a keeper 39, the 25 securing flanges of the latter being indicated at 40 and 41 after the fashion of the equivalent construction illustrated in Figure 12.

The arms of the U-shaped member 37 are 30 grooved as at 42 and the bearing portion of the keeper 39, in this instance, indented or depressed as at 43 to permit the hinge member 27 to have freedom of rotative movement while at the same time being held against endwise displacement of the arms 38 from the keepers 39.

35 The foregoing described hinging feature of the ironing board is not claimed herein inasmuch as the claims thereto are withdrawn from the instant application for a co-pending divisional case.

The means for enabling attachment of the ironing board to a handy piece of furniture, as when the same is supported on the partially opened drawer of a dresser, desk or the like, the inner member or section 21 of the board is provided with a pair of hooks 44 projected outwardly from 40 the inner end of the ironing board and adjustably held thereon through the medium of elongated hook shanks 45, slidably mounted endwise on the under face of the board, the shanks being of relatively thin formation so as to move approximately in the plane of the under face of the board to present no substantial obstructions beyond said plane when the under surface of the board is rested on the upper edge of the drawer and the hooks engaged with the customary bridge piece found above the drawer opening. Preferably there are two of these hooks and shanks as illustrated, one near each edge and running parallel with the edges of the board (Figure 2).

The underpart of the board is provided with 50 upwardly extending recess or groove portions 46 complementary to the shanks 45 of the hooks, these groove portions being of a length commensurate with the length of the hook shanks when they are in closed position (Figure 4), but sufficiently 55 long to accommodate a number of detents to cooperate with latching means for the various positions of adjustment of the shanks and their hooks.

The detents referred to are represented at 60 47 and are constituted by inwardly turned flanges of a plate 48 embedded in the bottom of the board section 21 and having intermediate the detents 47 arched or connecting members 49 spaced upwardly from the detents 47 providing therebetween guideways 50 for a widened and raised end

51 at the outer end of the shank 45, the guide portions confining the end of the shank against dropping away from the board in all positions of adjustment of the hook, the opposite or hook end of the shank being securely held in place by sliding through and over a U-shaped guide 52, formed by offsetting the plate 48 at the inner end portion of the plate, and oppositely offsetting the plate at 52'.

From the construction just described it will be seen that the shanks of the hooks may be moved outwardly or inwardly, being guided and confined at all times to the horizontal portions of the shanks by the head portions 51 passing between the detents 47 and the members 49, or ways 50. The latching means for engaging the detents 47 comprises a T-shaped member 53 composed of wire, the stem portion 54 of which is coiled into springs 55 extended in opposite directions and sleeved upon a rod 56, riveted at its ends 57 to the raised or offset end or head 51 of the shank 45, the free ends 58 of the springs projecting in a direction opposite to the stem portion 54 and impinging upon the under surface of the offset end 51 to normally force the T-head of the structure upwardly and hold the same in position to automatically engage any one of the detents 47 as determined by the adjustment of the hook towards or from the inner end of the board.

The T-head of the latch is specially formed by extending the wires constituting the stem outwardly in opposite directions (Figure 3) then upwardly as at 59 to give adequate height to the latch, and then by return bend 60 downwardly where the midportion of the latch is formed into an eye 61 to accommodate a pull ring 62 adapted to be engaged by the fingers of the user to pull the T-head of the latch downwardly and release the same from an engaged pair of detents to permit sliding of the hook shank to another position of adjustment.

It will be understood that the means for guiding and latching the hooks in position, apart from the hook shanks and latching means per se, may all be formed of a single piece of metal and readily installed in the board section 21, as by rivets or the equivalent 63, the end of the board itself being reinforced by having the inner end of the plate 48 passing upwardly over the end face of the board as at 64 and over the top of the board as at 65.

Where desirable the surfaces and corners of the board may be provided with rubber or felt surfacing to prevent marring the finish of the furniture to which the board is secured, as for example, by pads 66 on the inner end of the board section 21 and the similar lining 67 on the upper face of the shank 45 of the hook. The rubber lining 67 on the upper face of the shank 45, as clearly indicated in Figure 5, is of slightly less width than the shank to save the rubber from impairment by rubbing on the metal edges or surfaces of the metal guiding portions of the device, it being noted that the oppositely offset portion 52', cooperating with the guide 52, is spaced upwardly a sufficient distance to leave a space 52a through which the rubber may freely pass while the edges of the metal shank bear against the shoulders 52b, of the member 52' thereby avoiding any wear on the rubber. A similar formation of the metal 64, at the end of the board, provides a similar space 52c directly above the guide 52 so that at this point the edges of the metal shank 67 will work against the metal edge of the plate 64 and the rubber lining will have

free passage, that is, without rubbing contact, through the said space 52c.

The formation of the latch 53 is efficient and strong for the purposes herein intended, it being pointed out that the same is conveniently made up of steel wire having a springy characteristic and coiled as at 55, but it may be desirable, in instances, to further reinforce the T-head 53, and in such case the space 68 between the opposite portions of the wiring of the T-head may be connected by a supplemental strip or piece of metal 69 secured to the opposite ends or return bend portions of the T-head,—see Figure 19.

In Figure 20 a slightly modified form of the hook shank, here represented at 70, is shown, the same having an upwardly bent reduced or neck portion 71, connected with a head portion 72. This form enables the making of the hook and shank of a strip of metal of uniform width throughout in lieu of having the outwardly extending head portion or flanges 51 of the previously mentioned embodiment of the invention, it being understood that, where used, the instant form of hook and shank will, of course, be such that the head portion 72 will ride in the ways formed beneath the flanges forming detents 47.

I claim:

1. A portable ironing board having longitudinally extending channels at its inner end and securing means in the channels for temporarily attaching the board to an article of furniture, the securing means comprising hooks and guide members for the hooks, each of the hooks including an elongated shank, a head portion at the end of the shank, an offset portion in the shank adjacent to the head portion, and a latch mounted on the head portion, each of the guide members comprising a plate having a guide adjacent to the inner end of the board for receiving the shank of one of the hooks, a plurality of spaced U-shaped strap members pressed upwardly from the plate to provide a top and side walls of a guideway, and horizontal, inwardly directed spaced extensions providing a bottom wall for the guideway and abutments to be engaged by the latch, the head portion of one of the hooks being slidably received in the guideway.
2. A portable ironing board having longitudinally extending channels at its inner end and securing means in the channels for temporarily attaching the board to an article of furniture, the securing means comprising hooks and guide members for the hooks, each of the hooks including an elongated shank, a head portion at the end of the shank, an offset portion in the shank adjacent to the head portion, and a latch mounted on the head portion, each of the guide members comprising a plate having a flange at one end bent to engage the end and top surfaces of the board, a guide adjacent to said flange to receive the shank of one of the hooks, a plurality of spaced U-shaped strap members pressed upwardly from the plate to provide a top and side walls of a guideway, and horizontal, inwardly directed spaced extensions providing a bottom wall for the guideway and abutments to be engaged by the latch, the head portion of one of the hooks being slidably received in the guideway.
3. A portable ironing board having longitudinally extending channels at its inner end and securing means in the channels for temporarily attaching the board to an article of furniture, the securing means comprising hooks and guide

members for the hooks, each of the hooks including an elongated shank, a head portion at the end of the shank, an offset portion in the shank adjacent to the head portion, and a latch mounted on the head portion, each of the guide members comprising a plate having a guide adjacent to the inner end of the board for receiving the shank of one of the hooks, a plurality of spaced U-shaped strap members pressed upwardly from the plate to provide a top and side walls of a guideway, and horizontal, inwardly directed spaced extensions providing a bottom wall for the guideway and abutments to be engaged by the latch, the head portion of one of the hooks being slidably received in the guideway, said guide comprising a U-shaped strap pressed downwardly from the plate and a web in the plate adjacent to the downwardly pressed U-shaped strap.

4. A portable ironing board having longitudinally extending channels at its inner end and securing means in the channels for temporarily attaching the board to an article of furniture, the securing means comprising hooks and guide members for the hooks, each of the hooks including an elongated shank, a head portion at the end of the shank, an offset portion in the shank adjacent to the head portion, a latch mounted on the head portion, and a furniture protecting pad secured to the shank, each of the guide members comprising a plate having a guide adjacent to the inner end of the board for receiving the shank of one of the hooks, a plurality of spaced U-shaped strap members pressed upwardly from the plate to provide a top and side walls of a guideway, and horizontal, inwardly directed spaced extensions providing a bottom wall for the guideway and abutments to be engaged by the latch, the head portion of one of the hooks being slidably received in the guideway, said guide comprising a U-shaped strap pressed downwardly from the plate and a web in the plate adjacent to the strap having a depression therein and said pad being of less width than the shank and freely passing through the depression in the web.

5. A portable ironing board having longitudinally extending channels at its inner end and securing means in the channels for temporarily attaching the board to an article of furniture, the securing means comprising hooks and guide members for the hooks, each of the hooks including an elongated shank, a head portion at the end of the shank, an offset portion in the shank adjacent to the head portion, and a latch mounted on the head portion, each of the guide members comprising a plate having a guide adjacent to the inner end of the board for receiving the shank of one of the hooks, a plurality of spaced U-shaped strap members pressed upwardly from the plate to provide a top and side walls of a guideway, and horizontal, inwardly directed spaced extensions providing a bottom wall for the guideway and abutments to be engaged by the latch, the head portion of one of the hooks being slidably received in the guideway, said latch including a T-shaped head and spring means for holding the T-shaped head in position to rest on the U-shaped strap members and to engage with the horizontal extensions.

6. A portable ironing board having longitudinally extending channels at its inner end and securing eans in the channels for temporarily attaching the board to an article of furniture, the securing means comprising hooks and guide members for the hooks, each of the hooks including an elongated shank, a head portion at the end of the shank, an offset portion in the shank adjacent to the head portion, and a latch mounted on the head portion, each of the guide members comprising a plate having a guide adjacent to the inner end of the board for receiving the shank of one of the hooks, a plurality of spaced U-shaped strap members pressed upwardly from the plate to provide a top and side walls of a guideway, and horizontal, inwardly directed spaced extensions providing a bottom wall for the guideway and abutments to be engaged by the latch, the head portion of one of the hooks being slidably received in the guideway, said latch comprising a T-shaped head formed from spring wire and a stem portion coiled to form a spring for yieldably holding the T-shaped head in position to rest on the U-shaped strap members and to engage with the horizontal extensions.

7. A portable ironing board having longitudinally extending channels at its inner end and securing means in the channels for temporarily attaching the board to an article of furniture, the securing means comprising hooks and guide members for the hooks, each of the hooks including an elongated shank, a head portion at the end of the shank, an offset portion in the shank adjacent to the head portion, and a latch mounted on the head portion, each of the guide members comprising a plate having a guide adjacent to the inner end of the board for receiving the shank of one of the hooks, a plurality of spaced U-shaped strap members pressed upwardly from the plate to provide a top and side walls of a guideway, and horizontal, inwardly directed spaced extensions providing a bottom wall for the guideway and abutments to be engaged by the latch, the head portion of one of the hooks being slidably received in the guideway, said latch comprising a T-shaped head formed from spring wire, a reinforcing plate attached to the head, and a stem portion coiled to form a spring for yieldably holding the head in position to rest on the U-shaped strap members and to engage with the horizontal extensions.
